UNITED STATES PATENT OFFICE.

ALBERT FECHNER, OF POSEN, GERMANY.

HORSESHOE.

SPECIFICATION forming part of Letters Patent No. 499,976, dated June 20, 1893.

Application filed March 2, 1893. Serial No. 464,411. (No model.)

To all whom it may concern:

Be it known that I, ALBERT FECHNER, smith, of 6 Russische Strasse, Czarnikau, Posen, in the Empire of Germany, have invented a new 5 and useful Improvement in Means for Roughing Horseshoes, of which the following is a specification, reference being had therein to the accompanying drawings.

The present invention relates to a device 10 for the purpose of enabling a horse-shoe for summer wear to be quickly turned into one for winter wear by fixing in a suitable manner a steel hoop or removable shoe underneath the permanent horse-shoe.

15 The device can be used on horse-shoes for either riding or driving horses.

The device is represented in the accompanying drawings as adapted to horse-shoes for summer wear and also to one for the winter 20 season.

Figure 1 is an under side view of a horse-shoe for a riding horse with the steel hoop or removable roughing shoe fixed thereon. Fig. 2 represents the same shoe partly in front 25 elevation and partly in cross section. Fig. 3 is a similar view to Fig. 1 but without the steel hoop or removable shoe. Fig. 4 is a side elevation of Fig. 3. Fig. 5 is a longitudinal sectional elevation through the steel hoop or 30 removable shoe only. Fig. 6 is a perspective view of a toe calk with its upper clip. Fig. 7 shows the front part of the horse shoe in perspective, but without the toe calk and clip. Fig. 8 is a perspective view of a heel 35 calk with hook-shaped fastener for the rear. Fig. 9 is an under side view of a shoe for a driving horse with steel hoop or roughing shoe attached. Fig. 10 is an under side view 40 of the same with the steel hoop or roughing shoe removed therefrom. Fig. 11 is a side elevation of the same.

The riding horse-shoe is bent from a flat iron bar and is similar to the usual machine made shoe, provided with holes for the nails 45 and a channel or groove for the reception of the nail heads. The toe calk *e* is fixed underneath the shoe by means of a countersunk screw and is formed in one piece with the clip *g*, which latter is made to fit into a suitable recess in the toe of the shoe and is provided with a hole to fit over the pin *z* shown 50 in Fig. 7. The calks *f*, Fig. 8, are provided

with a hook shaped part or claw *n* which fits in a corresponding slot in the horse-shoe. The said calks are also fixed to the horse's shoe by 55 means of screws with countersunk heads.

In order to roughen the horseshoe it is only necessary to unscrew the toe calk *e* and heel calks *f* and fix the steel hoop or roughing shoe *b* on the shoe *a*. The steel hoop *b* is provided 60 with hooks *d* exactly similar to those *n* of the heel calks *f* and also with a front clip *c*, which is made exactly like the clip *g* on the toe calk *e*.

In the driving horse-shoe the heel calks *f'* and the toe calks *e'* are made in one piece 65 with the shoe and only the clip *g'* is screwed on. The clip *g'* is fixed in the same manner as shown in Fig. 7. The heel calks *f'* are in this case provided with a slot for the reception of the hooks *d* of the steel hoop *b*. 70

In order to fix the steel hoop *b* to the driving horse shoe, the clip *g'* is taken off and the hooks *d* of the steel hoop *b* are introduced into their respective slots at the heel of the shoe and the front clip *c* is pressed over the 75 pin *z* which is of itself sufficient to hold the steel loop *b* in position by its own elasticity, and the screw *h* is inserted for extra security. When the frost is gone the steel hoop is taken off the shoe by unscrewing the screw *h*, and 80 by forcing a screw driver between the clip and the horse's hoof, the clip is caused to slip off the pin *z* and by now applying the screwdriver at the front of the steel hoop, the latter is pushed fully down and can then be 85 taken off.

The device herein described has the advantage over the ordinary screwed roughing studs that it can be used in connection with either light or heavy traffic as well as for riding 90 while the screwed roughing studs can only be used for light traffic and even then are liable to break easily.

For heavy traffic the roughening has hitherto been done by the adoption of special ice-nails or roughing studs and roughening of the calks. This roughing lasts for only two or three days, while the steel hoop herein described lasts for a long time. Moreover this improved manner of roughing prevents the 95 horses from hurting their legs as it forms a large surface which easily slides over the horses' legs and in cases where horses kick each other the injury resulting therefrom will 100

not be nearly so bad as when caused by ice studs, calks and the like. Finally this manner of roughing can be done quickly by anyone, while for fixing ice studs and roughing calks the shoe has to be taken off to be put in the fire which can only be done by a shoeing smith or farrier.

In order to prevent the snow from clogging under the horseshoe, a filling or pad of any 10 elastic material such as india rubber or cork can be pressed into the shoe.

What I claim as new, and desire to secure by Letters Patent of the United States, is—

1. The combination with a horseshoe having grooved heel pieces, of a removable and replaceable roughing shoe composed of an elastic steel hoop having its heel portion, provided with hooks for detachably engaging the

grooves in the heel-pieces of the shoe, substantially as described.

2. The combination with a horseshoe having a pin at its toe part and provided with grooved heel pieces, of a removable and replacing roughing shoe composed of an elastic steel hoop having an upward projection at its 25 toe part for engaging said pin, and hooks at its heel parts for detachably engaging the grooves in the heel pieces of the shoe, substantially as described.

In witness whereof I have hereunto set my 30 hand in presence of two witnesses.

ALBERT FECHNER.

Witnesses:

W. H. EDWARDS,
PAUL FISCHER.
